James Mager David Pratt, Volney Richmond; Troy N.Y.
Letters Patent No. 373, Dated May 20, 1851

The Schedule referred to in these Letters Patent and making part of the same

To all to whom these presents shall come

Be it known that we

James Mager, David Pratt, & Volney Richmond of the City of Troy, in
County of Rensselaer and State of New York have invented or produced
a certain new design for a Coal stove and that the following is a
full clear and exact description of the character which distinguishes
it from all other things before known reference being had to the
accompanying drawings making part of these specifications Fig. 1.
Showing our design to consist of certain ornamental plates of pec-
uliar shape and configuration to suit the purposes of the stove
to which it is adapted. The body of the stove stands upon a heavy
base the form of which is clearly shown in Fig. 2 and which is
surrounded by O. G. Oval O. and bead mouldings. The four plates
which form the body of the stove are shown in the front view in
Fig. 1. The two sides and front of the stove have in each a two
light window, surrounded by heavy Gothic bead work - under
each window is a sunk ornamented panel with heavy Gothic
arches over the same as seen in the drawings.

Fig 2 shows a horizontal section of the body of the
stove on the line C D in the bottom of the four side plates have
a heavy O. G. & bead moulding projection sitting on the base -
The top of these side plates have also a heavy cove moulding
projection on which the top of the stove rests - Fig 3. shows
the plan of the top which is formed of a combination of waved
O. G. Oval O. Cove and bead mouldings.

The top ornament or iron standing upon a round
base composed of a combination of O. G. & Cove Mouldings is

clearly shown in Fig. 1. Fig. 4 shows the horizontal section of the foot or base of the corn at B.

Fig. 5 shows the horizontal section of the body of the corn at A. The cover or cap of the corn is of open gothic work as seen in Fig. 6 and the top knot represents a cluster of acorns.

Having thus fully described our improvement and design what we claim therein as new and for which we desire to secure letters patent is the foregoing described form and configuration of the plates forming an ornamental design for a stove as represented and illustrated by the drawings.
